ELECTRIC TOASTER FOR WALLS OR COUNTER TOPS

Frank R. Swanson, Owosso, Mich., assignor to Swanson
Manufacturing Co., Owosso, Mich., a corporation of
Michigan

Filed Mar. 29, 1962, Ser. No. 69,490

Term of patent 14 years

(Cl. D81—10)

Fig. 1

Fig. 2

Fig. 3

Fig. 4

Fig. 5

FIG. 1 is a top plan view of an electric toaster for walls or counter tops showing my new design.

FIG. 2 is a front face elevational view thereof.

FIG. 3 is an end elevational view.

FIG. 4 is a rear elevational view, and

FIG. 5 is a top, front perspective view.

The fine vertical lines shown on the large control panel

and the lower right horizontal element represent a textured pattern.

I claim:

The ornamental design for an electric toaster for walls or counter tops, substantially as shown and described.
